UNITED STATES PATENT OFFICE.

HILMAR MUELLER, OF TRENTON, NEW JERSEY.

PRESS AND MEANS FOR OPERATING THE SAME.

1,232,711.

Specification of Letters Patent. Patented July 10, 1917.

Application filed March 21, 1914. Serial No. 826,147.

To all whom it may concern:

Be it known that I, HILMAR MUELLER, a citizen of the United States, residing at Trenton, in the county of Mercer and State of New Jersey, have invented certain new and useful Improvements in Presses and Means for Operating the Same, of which the following is a full, clear, and exact description, reference being had to the accompanying drawings.

This invention relates to press-operating mechanism, and more particularly to mechanism for operating presses which are used for the purpose of manufacturing tiles for flooring and similar purposes. As ordinarily constructed, these presses each comprise a die which is adapted to contain the material from which the tiles are made and a plunger coöperating with the die to compact the material to the desired extent. The plunger is non-rotatably operated by a screw which is threaded into a frame and provided with a large hand-operated fly wheel.

It is a well known fact that the product of such hand-operated machines generally deteriorates toward the latter part of the working day, as the operator then tires and is unable to perform the pressing operation as carefully and as efficiently as during the earlier hours of the day. Notwithstanding this objection, machines of the type referred to have always heretofore been manually operated and, in fact, it has been deemed impracticable to equip them with mechanical or electrical power devices for operating the same.

It is the general object of the invention disclosed herein to provide mechanism, in the shape of an attachment, whereby a machine of this type may be operated by power in such manner as to enable the pressing operation to be continued throughout the day and produce a product which is uniform throughout the entire period; also to provide a power driven machine of this character which shall possess all of the advantages of one operated by hand and which will produce a uniform product of the high character that is obtainable through machines of this type; also to produce a machine of this character wherein the output will be materially increased over that of the hand operated machines. Still further objects of the invention are to pro-

vide a machine of this character with automatically operating controlling devices whereby the power may be cut off and the machine reversed at certain predetermined times, and whereby efficiency and safety in operation are secured. Further and more detailed objects of the invention will appear hereafter in the specification.

In the drawings forming part hereof Figure 1 represents an elevation of a machine of the character referred to hereinbefore having my invention applied thereto; Fig. 2 is a detail in plan illustrating the yielding driving connection between the platen shaft and the adjacent motor-driven part; 70 while Figs. 3 and 4 are enlarged sectional details corresponding respectively to the lines 3—3 and 4—4 of Fig. 1.

My invention is preferably provided as an attachment to an existing type of machine,—one which has been used as a hand-power machine for a comparatively long interval of time. These machines comprise generally a base standard 1 supporting an inverted U-shaped frame 2, the branches of this frame being carried by a bed plate 3 which is mounted on top of the base standard 1. 4 denotes the die for the material which is to be pressed and 5 the coöperating platen which is reciprocated by a screw 6 threaded into the upper end of the frame 2. At its upper end, the screw 6 is provided with a wheel 7 rigidly connected thereto.

The parts thus far described are such as are ordinarily used in the hand operated presses to which reference has been made. The wheel 7, however, differs from those ordinarily employed with such presses in that it is not as large as is the case with the wheels of the earlier machines, wherein the operating wheel is also a fly wheel which allows the platen to be carried down by inertia for a certain distance of its travel. Because of a coöperating feature in the driving mechanism for the hand wheel 7, it is not necessary to make this wheel of such size as in the earlier machines.

For the purpose of driving the screw 6, a reversing electric motor 8 is employed, which may be carried on a bracket 9 bolted to one side of the frame 2. On end of the motor shaft 10 is journaled in a bracket 11 which is also bolted onto one side of the frame 2, the shaft 10 being provided with

a pinion 12 meshing with a gear 13 mounted on a shaft 14 which is journaled in a pair of arms 15 carried by and forming part of the bracket 11. The shaft 14 is provided with a bevel pinion 16 meshing with a large bevel gear 17 which is sleeved upon the screw 6 and which rests upon a collar 18 on top of the central portion of the frame 2. The gear 17 is provided with a pair of posts 19 which project upwardly through diametrically opposite blocks 20 mounted in arcuate guideways 21. These blocks are yieldingly connected to the wheel 7 by means of the springs 22, which are shown as mounted in the guideways, on opposite sides of the blocks 20 and on studs 23 24 carried respectively by the blocks and the opposed ends of the guideways.

25 denotes a motor reversing-switch of standard type comprising a shaft 26 which, by a rotary movement through a certain distance in one direction, is adapted to drive the motor 8, by a further rotary movement in the same direction to stop the motor, and by a rotary movement in the reverse direction to reverse the motor. A switch of this kind being well known to those skilled in the art, any detailed description of the switch itself will be unnecessary. The shaft 26 is provided at one end with an operating hand lever 27 and at its opposite end with a forked arm, the forks being indicated at 28 and 29. The forks extend parallel to each other and the fork 28 projects beyond the fork 29 and is curved, as shown in Figs. 3 and 4. 30 denotes a roller which is supported on a pin 31 extending between and carried by the forks 28 and 29.

The non-rotatable extension of the screw 40 6 which carries the platen 5 is mounted within a yoke 32 carried by an arm which is secured to that side of the frame 2 which is adjacent to the switch 25. 33 denotes a plate extending from the top of the non-rotatable extension 34 of the screw 6 which is slidable within the yoke 32, the plate 33 projecting toward the switch 25; and 35 denotes a rod depending from this plate and having sleeved thereon a curved arm 36 which is in the same vertical plane as the fork 28. The arm 36 is vertically adjustable on the rod 35 by means of the adjusting screw 37, which is threaded through the arm 36, a lock nut 38 being employed to retain the parts in adjusted position. 39 denotes a second rod depending from the plate 33, at one side of the rod 35 (see Fig. 3). 40 denotes a forked arm and 41 a dog which is pivoted to the arm in such manner that it is free to swing upwardly on its pivot and is provided with a beveled surface 41^a presented toward the arm 29. The arm 40 is vertically adjustable along the rod 39 by means of an adjusting screw 42 which is mounted on the plate 33 and has its lower

end threaded through said arm, being provided with a lock nut 43 similar to the lock nut 38. The dog 40 is in the same vertical plane as the fork 29 and is located below the arm 36.

44 denotes a bolt which is slidably mounted in the yoke 32 and has a beveled end 45 projecting toward and adapted to pass between the forks 28 and 29. This bolt is normally retained in a retracted position (that is, in a position wherein it will not engage the roller 30) by means of a bolt 46 which is adapted to slide in a vertically extending guideway 47 in the yoke 32. A coiled spring 48 is so connected to the bolt 44 as to move the same toward the switch lever 28, 29 when the locking bolt 46 is elevated. A similar spring 49 holds the beveled end of the last mentioned bolt in a notch 44^a in the first mentioned bolt, whereby such movement of the bolt 44 is normally prevented. The upper end of the locking bolt 46 is provided with an extension 50 having a screw 51 therein which is adapted to engage one arm 52 of a lever pivoted between lugs 53 on top of the yoke 32. The other arm 52^a of the lever is arranged to be engaged by a disk 54 projecting from and carried by the lower end of the screw 6.

With the parts constructed and arranged as described, the operation will be as follows:— Assuming the die 4 to have the tile-forming material therein and the screw 6 to be elevated, the operator moves the lever handle 27 downwardly, thereby elevating the forks 28 and 29, as shown in Figs. 1, 3, and 4 of the drawing, and closing the driving circuit of the motor 8. Through the connections heretofore described, the large bevel gear 18 is rotated in a direction to move the screw and the attached platen 5 downwardly, the rods 19 permitting this relative vertical movement between the wheel 7 and the bevel gear. Owing to the size and weight of this bevel gear, the said gear and the wheel 7 together constitute a fly-wheel of equal efficiency with the much larger fly-wheel heretofore employed. As the screw descends, the plate 33 carries downwardly the arms 36 and 40. The arm 40 being below the arm 36, the dog 41 will strike the fork 29, but will swing upwardly on its pivot on the arm 40, allowing the said arm to pass beneath the fork without operating the switch. When the platen 5 is sufficiently near the die 4, the arm 36 which is also movable with the screw and platen, strikes the projecting fork 28 and moves the same downwardly, thereby rocking the shaft 26 and cutting off the current supply to the motor through the switch. The press, after the motor is cut out, operates through the inertia of the compound fly-wheel until the platen 5 is exerting the highest pressure to which it is intended the tile-forming mate-

rial shall be subjected. At this stage, the forked arm 28, 29 occupies the first position shown in dotted lines in Fig. 4, with the roller 30 adjacent to the end of the bolt 44. 5 The disk 54 will then, however, have rocked the lever 52 to elevate the locking bolt 46 sufficiently to release the bolt 44. Thereupon the inclined surface 45 of this bolt acts upon the roller 30 to swing the forked arm 10 28, 29 to the second dotted-line position shown in Fig. 4, in which position the switch automatically reverses the motor.

As the screw 6 and the attached part rise, the dog 41 moves upwardly, engages the 15 fork 29, and rocks the shaft 26 to a position to cut off the motor. The inertia of the fly-wheel will then carry the screw and platen to the starting point. If it is desired to subject the material to a repressing action, the operator merely swings the switch lever 27 downwardly to the position shown in Fig. 4, whereupon the operations just described are repeated.

Should the motor fail, for any reason, to 25 stop upon its reversal or should the fly-wheel operate longer than contemplated, no harm can happen to the platen, screw and attached parts, as the rotation of the screw will merely cause the rods 19 to pass entirely through and be disengaged from the blocks 20 before the plunger or any of its attached parts can strike anything which could cause injury.

From the construction described, it will 35 be apparent that I am enabled, in a power driven machine, to give the same yielding or flexible pressure to the tile material as is now secured in and through hand-operated machines; also to give a re-pressing action, if it is desirable so to do. It is further evident that I am enabled to automatically cut off the motor before the impact of the platen against the die, allowing the remainder of the movement to be accomplished 45 through the inertia of the fly-wheel, and that the point at which the motor may be cut off can be varied as occasion may require, to produce corresponding variations in the pressure. A further advantage of my 50 construction resides in the fact that the motor is automatically reversed practically on impact—at such time as will avoid subjecting the parts to an undesirable high pressure. Furthermore, by the construction and 55 arrangement of parts, there will be a material interval of time between the reversals of the motor, which results in taking the strain off the motor and greatly extending the life thereof. A still further advantage 60 of the construction is that the motor can be operated only in the proper direction and that it is practically impossible to make a mistake in this regard.

While the motor-controlling devices are 65 shown here as applied to a tile-press and

while the arrangement and operation of the same are particularly designed with reference to such machines, it will be evident that they may, and probably will, be of more general application. Hence I do not wish 70 to be understood as limiting the invention herein only to machines of a special type, but reserve to myself the sole and exclusive right to apply to machines of any type 75 the devices covered by the combinations embodied in the claims hereto annexed.

Having thus described my invention, what I claim is:

1. The combination with a reciprocating impact member, of a motor for driving the 80 same, means controlled by the movement of said member for cutting off the motor before the impact of said member, and means also controlled by the movement of said member for reversing the motor substantially 85 at the end of the stroke of said member.

2. The combination, with a machine comprising a reciprocating member and a co-operating impact member of a motor for 90 driving the reciprocating member, means controlled by the movement of said reciprocating member for cutting off the motor before the impact of said reciprocating member, and means also controlled by the movement 95 of said reciprocating member for reversing the motor substantially on impact of said members.

3. The combination, with a reciprocating impact member, of a motor for driving the 100 same, means controlled by the movement of said member for cutting off the motor before the impact of said member, means also controlled by the movement of said member for reversing the motor substantially on the impact 105 of said member, and means controlled by the reverse movement of the said member for automatically cutting off the motor when said member shall have moved a predetermined distance in the reverse direction. 110

4. The combination, with a machine comprising a reciprocating member and a co-operating impact member, of a motor for driving the reciprocating member, means controlled by the movement of said reciprocating member for cutting off the motor before the impact of said reciprocating member, means also controlled by the movement 115 of said reciprocating member for reversing the motor substantially on impact of said members, and means controlled by the reverse movement of the reciprocating member for automatically cutting off the motor when said member shall have moved a predetermined distance in the reverse direction. 120

5. The combination, with a reciprocating impact member, a screw operating the same, and a fly wheel on said screw, of a motor, connections between said motor and said screw for rotating the same in reverse direc- 125

tions, means operative by the travel of the screw for automatically cutting off the motor before the impact of the reciprocating member, and means for automatically reversing the motor when said member shall have given its impact through the inertia of the fly wheel.

6. The combination, with a machine comprising a reciprocating impact member, a screw for operating the same, and a fly wheel on said screw, of a motor, connections between said motor and said screw for rotating the same in reverse directions, means operative by the travel of the screw for automatically cutting off the motor before the impact of the reciprocating member through the inertia of the fly wheel, and means for automatically cutting off the motor when said member shall have moved a predetermined distance in the reverse direction.

7. The combination, with a die and an impact platen of a motor, connections between said motor and said platen for reciprocating the latter, means for automatically cutting off the motor when the platen is within a predetermined distance of the die to permit the platen to travel the remainder of the distance to said die by inertia, and means for automatically reversing the motor when the pressure between the die and the platen reaches a predetermined point.

8. The combination, with a die and an impact platen of a motor, connections between said motor and said platen for reciprocating the latter, means for automatically cutting off the motor when the platen is within a predetermined distance of the die to permit the platen to travel the remainder of the distance to the die by inertia means for automatically reversing the motor when the pressure between the die and the platen reaches a predetermined point, and means for automatically cutting off the motor when the platen shall have moved a predetermined distance in the reverse direction.

9. The combination, with an impact platen, a screw for operating the same, and a wheel for operating said screw of a motor, driving connections between the motor and the wheel, said driving connections including a gear rotatable about the axis of the screw, pins projecting from said gear, blocks yieldingly connected to the hand wheel through which said pins may extend whereby to drive the hand wheel and the screw, and means controlled by the movement of the platen for stopping the motor when the platen shall have been driven a predetermined distance.

10. The combination, with an impact platen, a screw operating the same, and a wheel for operating said screw, of a motor,

driving connections between the motor and the wheel, said driving connections including a gear wheel rotatable about the axis of the screw, pins projecting from one of said wheels and blocks yieldingly connected to the other wheel through which said pins may extend whereby to drive the screw.

11. The combination, with an impact platen and a screw for advancing and retracting the same, of a motor, a yielding driving connection between the motor and the screw, and means for automatically cutting off the motor before impact of the platen, and means for reversing the motor after said impact.

12. The combination, with a reciprocating impact member having an inertia operating device, of a motor, a yielding driving connection between the motor and the reciprocating member, and means for automatically cutting off the motor before impact of said member.

13. The combination, with a reciprocating impact device, a screw for operating the same, and a fly wheel connected with said screw, of a motor, a yielding connection between the motor and the fly wheel, means controlled by the movement of said device for cutting off the motor before impact to allow the screw to be rotated by the inertia of the fly wheel, means for reversing the motor when the said device shall have been advanced a predetermined distance through such inertia, and means adapted to cut off the motor when said device shall have been moved a predetermined distance in the reverse direction.

14. The combination, with a reciprocating device, a screw for operating the same, and a fly wheel connected to the screw, of a motor, a yielding drive between the motor and the fly wheel, a switch for controlling the motor, said switch comprising a shaft, a pair of forks projecting from the shaft, and a roller between said forks, an arm movable with the reciprocating device and projecting toward one of the forks, a dog pivoted to said arm whereby it may pass said fork when moving in one direction but engage it when moving in the opposite direction, an arm movable with said member and projecting toward the other fork and adapted to engage the same and rock the shaft to cut out the motor, and a latch controlled by the movement of said member and adapted to engage the roller and move the shaft to a position to reverse the motor.

15. The combination, with a reciprocating device, of a motor, a driving connection between the motor and the said devices, a switch for controlling the motor, said switch comprising a shaft, a pair of forks projecting from the shaft and a roller between said forks, an arm movable with the reciprocating

ing device and projecting toward one of the forks, a dog pivoted to said arm whereby it may pass said fork when moving in one direction but engage it when moving in the 5 opposite direction, an arm movable with said member and projecting toward the other fork and adapted to engage the same and rock the shaft to cut out the motor, and a latch controlled by the movement of said 10 member adapted to engage the roller and

move the shaft to a position to reverse the motor.

In testimony whereof, I hereunto affix my signature in the presence of two witnesses.
